UNITED STATES PATENT OFFICE.

CLARENCE S. SNAVELY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 29, 1926. Serial No. 112,491.

My invention relates to railway traffic controlling apparatus, and particularly to apparatus of the type comprising train carried governing means controlled by energy received from the trackway.

One object of my present invention is the provision, in apparatus of the type described, of means for supplying the trackway with alternating currents periodically interrupted at different frequencies, and governing means on the train selectively responsive to the frequency of interruption of such currents.

I will describe one form of railway traffic controlling apparatus embodying my invention, and will then point out the novel features thereof in claims.

The accompanying drawing is a diagrammatic view showing one form of railway traffic controlling apparatus embodying my invention.

Referring to the drawing, the reference characters 1 and 1^a designate the track rails of a stretch of railway track over which traffic normally moves in the direction indicated by the arrow. These track rails are divided, by means of insulated joints 2, into a plurality of successive track sections A—B, B—C, etc. Each track section is provided with a track transformer designated by the reference character T with an exponent corresponding to the location and having a secondary 5 constantly connected with the rails adjacent the exit end of the section through the usual impedance 6. Each track section is further provided with a polarized track relay designated by the reference character R with a suitable distinguishing exponent and comprising two windings 8 and 9. One winding 8 of each track relay is constantly connected across the rails adjacent the entrance end of the associated section. The remaining winding 9 of each track relay is constantly supplied with alternating current from secondary 10 of an adjacent line transformer designated by the reference character J with an appropriate exponent and having its primary 11 constantly supplied with alternating current from a suitable source such as an alternator N over line wires 3 and 3^a. The track relays R may be used to control governing means, not shown in the drawing, in any suitable manner.

Associated with each track relay is a repeater relay designated by the reference char-

acter P with an exponent corresponding to the location and arranged to be energized only when the associated track relay is energized in one direction or the other. Referring particularly to relay P^B, the circuit for this relay may be traced from secondary 10 of transformer J^B, through wires 19, 20 and 21, contact 22 of relay R^B in the normal or reverse positions, wire 23, winding of relay P^B, and wires 24, 25, 26, 27 and 28 back to secondary 10 of transformer J^B.

Each track section is also provided with a coding relay designated by the reference character S with an appropriate exponent. Each coding relay S comprises two windings X and Y, each made up of two coils 14 and 15, and a pivoted armature controlled by the windings. The armature 16 controls two contacts 17 and 18, which are arranged to occupy one extreme position or the other according as armature 16 is attracted by winding X or winding Y. Associated with each relay S is a rectifier designated by the reference character Q with a suitable exponent. Referring particularly to relay S^B, when relay P^B is energized a circuit is closed from secondary 10 of transformer J^B, through wires 19, 29 and 29^a rectifier Q^B, wires 30 and 30^a, front contact 31 of relay P^B, wire 32, coil 14 of winding Y and coil 14 of winding X, wire 33, front contact 34 of relay P^B, wires 35 and 36, rectifier Q^B, and wires 71, 27 and 28, back to secondary 10 of transformer J^B. It will be seen that by virtue of this circuit, the coils 14 of windings X and Y are supplied from transformer J^B with direct current which flows through the coils in series. Coil 14 of winding X is provided with a shunting circuit which may be traced from the lower terminal of this coil, through wire 33, front contact 34 of relay P^B, wires 35 and 38, back contact 39 of relay R^A, wire 40, and contact 17—17^a of relay S^B to the upper terminal of coil 14 of winding X. When contact 17—17^b is closed coil 14 of winding Y is shunted through a circuit which may be traced from the lower terminal of coil 14 of winding Y, through wire 32, front contact 31 of relay P^B, wires 30^a and 41, and contact 17—17^b of relay S^B, back to the upper terminal of coil 14 of winding Y. As shown in the drawing armature 16 is swung toward winding X but relay R^A is energized, so that the shunting circuit for coil 14 of winding X is open. The

shunting circuit for coil 14 of winding Y is also open at contact 17-17^a, but armature 16 is held by winding X in such position that contact 17-17^a is closed because of the reduced air gap between armature 16 and winding X, though current is supplied to coils 14 of windings X and Y in series. Should relay R^A become deenergized, the shunting circuit for coil 14 of winding X would be closed. The magnetic field due to this coil would then gradually decay until the comparatively large attraction of coil 14 of winding Y would swing armature 16 toward winding Y. This reversal of the armature would open the shunt for coil 14 of winding X and would close the shunt around coil 14 of winding Y. After a time interval the increasing field of coil 14 of winding X would predominate over the decreasing field of coil 14 of winding Y and armature 16 would be swung back into the position in which it is illustrated in the drawing. It follows that when relay R^A is deenergized, relay S^B operates to close contact 18-18^a and contact 18-18^b intermittently.

When relay P^B is de-energized the operating circuit for relay S^B may be traced from secondary 10 of transformer J^B, through wires 19, 29, and 29^a, rectifier Q^B, wires 30 and 30^a, back contact 31 of relay P^B, wire 37, coils 15 and 14 of winding Y, coils 14 and 15 of winding X in series, wire 70, back contact 34 of relay P^B, wires 35 and 36, rectifier Q^B, and wires 71, 27 and 28 back to secondary 10 of transformer J^B. If relay R^A is de-energized when relay P^B is de-energized, a shunting circuit for winding X is closed each time contact 17-17^a of relay S^B closes. This shunting circuit passes from the lower terminal of this winding through wire 70, back contact 34 of relay P^B, wires 35 and 38, back contact 39 of relay R^A, wire 40, contact 17-17^a of relay S^B and back to the upper terminal of winding X. Similarly a shunting path of low resistance is closed around winding Y when contact 17-17^b of relay S^B is closed from the lower terminal of winding Y, through wire 37, back contact 31 of relay P^B, wires 30^a and 41, contact 17-17^b of relay S^B and back to the upper terminal of winding Y. It follows therefore that when relay P^B is de-energized and relay R^A is also de-energized the operation of relay S^B alternately closes contact 18-18^a and contact 18-18^b. It should be pointed out that when relay P^B is energized only coils 14 of windings X and Y are included in the operating circuit for relay S^B, but that when relay P^B is de-energized, both coils of windings X and Y are included in the operating circuit. Due to the increased reactance of the windings X and Y when both coils are included in the circuit, the operation of the relay is more rapid when only one coil of the winding is included in the operating circuit than when

both coils are included in the circuit. The relays S may be arranged to operate at any reasonable speeds but for purposes of illustration I will assume that when relay P^B is energized relay S^B operates at 100 cycles per minute and that when relay P^B is de-energized, relay S^B operates at 30 cycles per minute. It will be noted that when relay S^B is operated at either speed, if back contact 39 of relay R^A becomes open the shunt around that portion of winding X which is then included in the operating circuit is opened and when the armature 16 next swings toward winding X, the operation of the relay ceases and the armature remains in that position until back contact 39 of relay R^A is again closed.

When relay R^A is energized in one direction or the other, so that relay S^B is at rest, contact 18-18^a of relay S^B is closed and current is supplied without interruption to the primary 7 of transformer T^B from secondary 10 of transformer J^B in the manner I will now describe. If relay P^B is energized, current is supplied from secondary 10 of transformer J^B, through wires 19 and 29, contact 18-18^a of relay S^B, wires 56 and 57, contact 58 of relay R^B, wire 59, front contact 60 of relay P^B, wire 61, primary 7 of transformer T^B, wire 62, front contact 63 of relay P^B, and wires 64, 26, 27 and 28, back to secondary 10 of transformer J^B. This circuit is closed only when relays P^B and R^B are energized and when contact 18-18^a of relay S^B is closed, under which condition current of normal relative polarity is supplied to the rails of section A-B, thereby swinging contacts 22, 58 and 39 of relay R^A to the right. When relay P^B is de-energized, however, current from secondary 10 of transformer J^B flows through wires 19 and 29, contact 18-18^a of relay S^B, wires 56 and 65, back contact 63 of relay P^B, wire 62, primary 7 of transformer T^B, wire 61, back contact 60 of relay P^B, and wires 64, 26, 27 and 28 back to secondary 10 of transformer J^B. When this circuit is closed current of reverse relative polarity is supplied to the rails of section A-B and relay R^A is energized in the reverse direction so that the contacts of this relay are swung to the left.

Means are also provided for at times supplying each track section with interrupted alternating train controlling current. The immediate source of this train controlling current for each track section is a transformer designated by the reference character K with an exponent corresponding to the location and having a primary 13 constantly supplied with alternating current from a suitable source such as an alternator M over line wires 4 and 4^a. The frequency of the current supplied by alternator N is different from that supplied by alternator M and since current from alternator N is supplied to the track-way for energizing the track relays these re-

lays are constructed to respond only to current of the frequency delivered by alternator N. For purposes of illustration I will assume that the track circuit current supplied 5 to the rails of each section from the associated transformer J is of 60 cycles per second and that the current supplied to each transformer K by alternator M is of 100 cycles per second but these particular frequencies are not essential and have been mentioned simply for purposes of illustration.

Train controlling current is supplied to the rails of a section only when the coding relay S for that section is operating. For 15 example, when relay P^B is energized and when relay R^A is de-energized to operate relay S^B at 100 cycles per minute, an impulse of train controlling current is supplied to primary 7 of transformer T^B, for each cycle of operation 20 of relay S^B, the circuit being traced from secondary 12 of transformer K^B, through wire 42, contact 18-18^b of relay S^B, wires 56 and 57, contact 58 of relay R^B, wire 59, front contact 60 of relay P^B, wire 61, primary 7 of 25 transformer T^B, wire 62, front contact 63 of relay P^B, and wires 64, 26, 27 and 43, back to secondary 12 of transformer K^B. When relays R^B and P^B are energized, then, and when relay S^B is operating, the rails of the section 30 A-B are supplied with an impulse of train controlling current each time contact 18-18^b of relay S^B is closed, and with an impulse of track circuit current each time contact 18-18^a is closed. It follows that the rails of the section 35 are then supplied with alternate impulses of train controlling current and track circuit current, the frequency of the impulses of each current being 100 cycles per minute. Train controlling current supplied to the rails at this frequency of interruption I shall term 40 the "proceed code". When relay P^B is de-energized and when relay S^B is operating, an impulse of train controlling current is supplied as before to the trackway each time contact 18-18^b is closed, the circuit for transformer T^B then passing from secondary 12 of transformer K^B, through wire 42, contact 18-18^b of relay S^B, wires 56 and 65, back contact 63 of relay P^B, wire 62, primary 7 of 45 transformer T^B, wire 61, back contact 60 of relay P^B and wires 64, 26, 27 and 43 back to secondary 12 of transformer K^B. When this circuit is closed and when relay R^A is de-energized relay S^B operates at 30 cycles per 50 minute, and the rails of section A-B are supplied with alternate impulses of train controlling current and of track circuit current, the frequency of interruption of each current being 30 cycles per minute. Train 55 controlling current supplied to the rails of the section in the form of impulses having a frequency of 30 cycles per minute, I shall term the "caution code".

As shown in the drawing the section to the 60 right of point C is occupied by a train indi-

cated diagrammatically at V. Relay R^C is therefore de-energized and relay P^C is also de-energized. Track circuit current of reverse relative polarity is therefore supplied to the rails of section B-C. Relay R^B is therefore 70 energized in the reverse direction so that relay S^C is at rest and the track circuit current supplied to section B-C is uninterrupted. No train controlling current is supplied to the rails of section B-C. Relay P^B is energized and track circuit current of normal relative polarity is therefore supplied to the rails of section A-B. Relay R^A is therefore 75 energized in the normal direction so that relay S^B is at rest and the track circuit current supplied to section A-B is uninterrupted. In similar manner relay P^A is energized, but the section to the left of point A is occupied by a second train V^a, so that the track relay for this section is de-energized and relay S^A 80 is operating at 100 cycles per minute. The rails of the section to the left of point A are therefore supplied with train controlling current in the form of a proceed code, and during the interval between successive impulses of such train controlling current, track circuit current of normal relative polarity is supplied to the rails of the section. 85

Carried upon the train V^a in advance of the forward axle is a receiver W comprising two magnetizable cores 66 and 66^a located in inductive relation with the track rails 1 and 1^a respectively. Core 66 is provided with a winding 67, and core 66^a is provided with a similar winding 67^a, the two windings 67 and 67^a being connected in series in such manner that the voltages induced therein by train controlling currents flowing in opposite directions in the two track rails at an instant are additive. The windings 67 and 67^a of the receiver W are connected, through an amplifier 68 and a rectifier 69 with a relay D. By means of a condenser 80, the windings 67 and 67^a are tuned to resonance at the frequency of the train controlling current so that the 100 relay D is energized by train controlling current but not by 60 cycle track circuit current in the track rails. It follows that relay D is intermittently energized when the rails occupied by the train V^a are supplied with train 105 controlling current, the frequency of energization of relay D corresponding to the frequency of interruption of such train controlling current. 110

The reference characters G¹ and G² designate two transformers each comprising a magnetizable core 44 and a secondary 47. When relay D is intermittently energized, periodically varying fluxes of a frequency corresponding to the frequency of energization of relay D are created in the cores of transformers G¹ and G². As here shown this is accomplished by providing each transformer 125 with two primaries 45 and 46. When relay D is energized, direct current is supplied 130

from a suitable source such as a battery F, to primaries 45 of transformers G¹ and G² in parallel. When relay D is de-energized, however, direct current flows through primaries 46 of these transformers in parallel from battery F. It will be noted that current flows in opposite directions through the two primaries of each transformer and it follows that when relay D is being energized 5 intermittently by the interrupted train controlling current, the magnetic fluxes in transformers G¹ and G² are periodically reversed at a frequency corresponding to the frequency of interruption of the train controlling current received by relay D. Secondary 47 of transformer G¹ is connected, through a rectifier L¹, with a direct current relay E¹. The rectifier L¹ may be of any suitable type and as here shown comprises four asymmetrical 10 units 48 so arranged that current in relay E¹ always flows in a direction from the right-hand terminal to the left-hand terminal of the relay. The variations in the flux in the core of transformer G¹ create surges of current in 15 relay E¹, and to assist the relay in holding closed its front contact during successive surges I connect an asymmetrical unit 49 in parallel with the relay E¹. This unit 49 is arranged to offer a high resistance to current supplied from rectifier L¹, but to offer 20 a low resistance to current resulting from the decaying field of the relay winding during the interval of time between successive impulses supplied to the relay. The snubbing 25 effect of the unit 49 therefore renders relay E¹ slow releasing but does not interfere with the quick pick-up of the relay. It should also be pointed out that the asymmetrical units of rectifier L¹ assist in this snubbing effect, the 30 units 48 comprising two parallel paths each containing two of the units in series and conducting current in the same direction as unit 49 during the decay of the field of relay E¹.

In similar manner a second relay E² is connected with secondary 47 of transformer G² through a rectifier L² and is provided with an asymmetrical unit 49 connected in parallel therewith.

It is well known that if a transformer is 35 designed so that for an input electromotive force of one amplitude and frequency the core is substantially saturated, a certain amount of energy will be delivered at that frequency and at least as much energy will be delivered 40 at higher frequencies, but that at lower frequencies with the same amplitude of electromotive force a smaller amount of energy is delivered by the transformer. I take advantage of this principle to select between the 45 caution and proceed codes on board the train.

This is accomplished by so proportioning the parts that when the flux in transformer G¹ is being reversed 30 times per minute, as when relay D is receiving the caution code, the 50 core of the transformer is substantially satu-

rated and relay E¹ is supplied with sufficient energy to pick up the relay. It follows that relay E¹ will also be energized when the flux is being reversed 100 times per minute, as when relay D is receiving the proceed code. 70 Transformer G² is so proportioned that when the flux is being reversed 100 times per minute, its core is substantially saturated and sufficient energy is supplied to relay E² to pick up the relay. When the caution code is being 75 received, however, relay E² is de-energized, because the reversals of flux are of the same amplitude as for the proceed code, due to the saturation of the core, and since they are less rapid the energy supplied to the relay E² is 80 not sufficient to energize the relay.

I will now assume that the train V^a proceeds through the stretch of track shown in the drawing. While the train is in the section to the left of point A, the proceed code supplied to the rails of this section energizes relay D intermittently at the rate of 100 cycles per minute. Relays E¹ and E² are therefore both energized so that current flows from battery F, through front contact 51-51^a 90 of relay E² to lamp 53, lighting this lamp to indicate proceed. As the train enters section A-B, the de-energization of relay R^A sets relay S^B into operation. Relay P^B is energized and relay S^B therefore operates at 100 95 cycles per minute. The rails are therefore supplied with train controlling current in accordance with the proceed code so that as the train proceeds through section A-B relays E¹ and E² remain in their energized conditions and 100 lamp 53 remains lighted to indicate proceed. As the train enters section B-C, relay R^B becomes de-energized and sets relay S^C into operation. Relay P^C is de-energized, however, so that relay S^B operates at 30 cycles per 105 minute. Train controlling current is therefore supplied to the rails of section B-C in accordance with the caution code. Relay D is therefore energized intermittently 30 times each minute. As a result the fluxes in transformers G¹ and G² are reversed 30 times each minute. The energy thus supplied to relay E² is not sufficient to hold this relay in its energized condition so that this relay opens 110 but relay E¹ is held in its energized condition. Current then flows from battery F, over back contact 51-51^b of relay E² and front contact 52-52^a of relay E¹ to lamp 54, energizing this lamp to indicate caution. Should the train enter the section to the right of point C, relay 120 D would be deprived of train controlling current and would be continuously de-energized so that relays E¹ and E² would both be de-energized and current from battery F would flow to lamp 55 over back contact 51-51^b of 125 relay E² and back contact 52-52^b of relay E¹. Lamp 55 would then be lighted to indicate stop.

When the train passes out of section A-B, the next impulse of track circuit current ener- 130

gizes relay R^A and opens the shunt around the portion of winding X then included in the operating circuit for relay S^B , thereby causing the operation of this relay to cease, and discontinuing the interruption in the track circuit current supplied to the section. At the same time the stopping of relay S^B completely interrupts the supply of train controlling current to the rails of the section. In similar manner when a train leaves any of the remaining sections the operation of the coding relay for that section immediately ceases and uninterrupted track circuit current is thereafter supplied to the rails of the section as long as the section is unoccupied.

10 In this application I have shown the coding relays S provided with only two coils in each winding to give two speeds for the relay, and the train carried apparatus is arranged to select between only two frequencies of the interruptions of the train controlling current, but it should be clearly understood that 15 this limitation is not necessary and that any reasonable number of codes of different frequencies could be used.

20 Although I have herein shown and described only one form of railway traffic controlling apparatus embodying my invention, it is understood that various changes and modifications may be made therein within the scope of the appended claims without departing from the spirit and scope of my invention.

25 Having thus described my invention what I claim is:

1. In combination, a source of periodically varying electromotive forces of constant amplitude but different frequencies, a transformer having a primary receiving energy from said source and a core substantially saturated when the primary is supplied with an electromotive force of one frequency, and a current consuming device connected with the secondary of said transformer and requiring for its operation the amount 45 of power supplied thereto when the primary of the transformer is receiving an electromotive force of such one frequency.

2. In combination a transformer, means for supplying the primary of said transformer with periodically varying electromotive forces of different frequencies but constant amplitude, and a current consuming device connected with the secondary of said transformer and arranged to be operated only if the primary of the transformer is supplied with an electromotive force at a frequency at least as great as that required to substantially saturate the transformer core.

3. In combination, a source of direct current, a contact operating at times at different frequencies, a transformer having a primary connected with said source through said contact, the core of said transformer being substantially saturated when said contact is operating at one frequency, and a cur-

rent consuming device connected with the secondary of said transformer and arranged to be operated only when said contact is operating at said one frequency or at a higher frequency.

4. In combination, a source of periodically varying electromotive forces of constant amplitude but different frequencies, two transformers each having a primary receiving energy from said source and the cores of said transformers being substantially saturated at different frequencies of the electromotive forces, and two current consuming devices one connected with the secondary of each transformer and each arranged to be energized only when the frequency of the electromotive force applied to the associated primary is equal to or above the frequency required to saturate its core.

5. Railway traffic controlling apparatus comprising a train carried relay at times energized intermittently at different frequencies, two transformers each having a primary supplied with periodically varying current the frequency of which depends upon the frequency of energization of said relay, the cores of said transformers being substantially saturated at different frequencies of the current supplied to the associated primaries, and governing means selectively controlled by 90 said transformers in accordance with the frequency of energization of said relay.

6. Railway traffic controlling apparatus comprising a train carried relay at times energized intermittently at different frequencies, two transformers each having a primary supplied with periodically varying current the frequency of which depends upon the frequency of energization of said relay, two other relays one connected with the secondary of each said transformer, a rectifier interposed between each such relay and the associated transformer secondary, and governing means selectively controlled by said other relays in accordance with the frequency of energization of said train carried relay.

7. In combination, two transformers, means for supplying the primaries of both said transformers with periodically varying electromotive forces of different frequencies, and two current consuming devices one connected with the secondary of each transformer, the transformer cores being substantially saturated at different frequencies of the electromotive forces supplied to the primaries thereof so that the devices are energized only when the frequencies of said electromotive forces are above different values.

8. Railway traffic controlling apparatus comprising a train carried relay at times energized intermittently at different frequencies, two transformers having different saturation characteristics, means controlled by said relay for creating in said transformers periodically varying fluxes the frequencies of

- which vary in accordance with the frequency of energization of said relay, two selector relays one connected with the secondary of each transformer, a rectifier interposed between each such selector relay and the associated transformer secondary, and governing means selectively controlled by said selector relays in accordance with the frequency of energization of said train carried relay.
10. In combination, two transformers, means for at times creating in the cores of said transformers periodically varying fluxes of one frequency and for at other times creating in such cores periodically varying fluxes of a different frequency, one core being saturated by flux of the first frequency and the other core being saturated by flux of the other frequency, two current consuming devices one connected with the secondary of each transformer and each arranged to be energized only when the associated transformer is being supplied with flux at a frequency at least as high as the frequency at which the core of such transformer becomes saturated.
15. 10. In combination a first relay at times intermittently energized at different frequencies, two transformers, means controlled by said first relay for supplying current to the primaries of said transformers, two relays one connected with the secondary of each transformer and so arranged that one relay is energized when the frequency of energization of said first relay is above a predetermined low value and below a predetermined higher value but that both said relays are energized when the frequency of energization of said first relay is above said higher value.
11. In combination, a stretch of railway track, a contact, means for operating said contact intermittently at different speeds, and means including said contact for supplying current to the stretch.
16. In combination, a stretch of railway track, a coding relay comprising a contact arranged to be periodically closed at different frequencies, and means controlled by said contact for supplying alternating current to the rails of said stretch.
17. In combination, a stretch of railway track, a contact, a source of alternating current, means including said contact for connecting said source with the rails of the stretch, and means for at times repeatedly opening and closing said contact at different speeds.
18. In combination, a stretch of railway track, a coding relay comprising a contact at times operated intermittently, means for varying the speed of operation of said contact, a first source of alternating current, means including said contact for at times connecting said first source with the rails of the stretch, a second source of alternating current, and means effective only when said first source is disconnected from the rails for connecting said second source with the rails of the stretch.
19. In combination, a stretch of railway track, means including a coding relay for supplying the rails of the stretch with alternate impulses of alternating currents of different frequencies, and means for at times varying the speed of operation of said coding relay to vary the frequency of the impulses supplied to the trackway.
20. In combination, a stretch of railway track, a multiple speed coding relay comprising a movable armature, two windings for moving the armature in opposite directions, means for supplying current to a selected portion of each winding, means controlled by said armature for alternately shunting such selected portion of said windings, a contact controlled by said armature, and means including said contact for at times supplying interrupted alternating current to the rails of the stretch.
21. Railway traffic controlling apparatus comprising a stretch of railway track, a multiple speed coding relay comprising a movable armature, two windings for moving the armature in opposite directions, means for supplying current to a selected portion of each winding, means controlled by said armature for alternately shunting such selected portion of said windings, a source of alternating current, a contact controlled by said armature, means including said contact for at times supplying the rails with alternating current interrupted at different frequencies depending upon the operating speed of the relay, and governing means on a train selectively responsive to such interruptions.
22. In combination, a stretch of railway track, a relay comprising a movable armature, two windings arranged when energized to move the armature in opposite directions, means for supplying current to said windings, means controlled by the armature for alternately shunting said windings, means controlled by said armature for supplying interrupted current to the stretch, and means effective when said stretch is unoccupied to prevent the shunting of one said winding to stop the relay.
23. In combination, a stretch of railway track, a relay comprising a movable armature, two windings arranged when energized to move the armature in opposite directions, means for supplying current to said windings, means controlled by the armature for alternately shunting said windings, means controlled by said armature and effective when the relay is operating to supply said stretch with alternate impulses of track circuit current and train controlling current, and means effective when the stretch is unoccupied to prevent the shunting of one of said winding

to stop the relay in such position that the stretch is supplied continuously with track circuit current.

20. Railway traffic controlling apparatus comprising means for supplying the track-way with alternating current having its amplitude periodically varied at different fre-

quencies, means for translating said variations into alternating currents of the same frequencies as the variations, and governing means selectively controlled by said last named current. 10

In testimony whereof I affix my signature.
